TAKE-OUT

Karl E. Peiler, West Hartford, Conn., assignor
to Hartford-Empire Company, Hartford, Conn.,
a corporation of Delaware

Application August 31, 1932, Serial No. 631,133

7 Claims. (Cl. 49—14)

This invention relates to takeout apparatus for the removal of articles of glassware, such as bottles, from the final molds of bottle forming machines of the Owens type, that is, machines in which the final molds open at a position in which the longer and normally vertical axis of the bottle or article being formed is at an angle to the vertical. The present invention constitutes an extension of and improvement upon the invention of my prior Patent No. 1,654,091, granted December 27, 1927, and is particularly intended to adapt the structure of this prior patent to the removal of articles from machines of the Owens type.

Among the objects of the present invention is to provide a device for the efficient removal or taking out of bottles or other articles from the final molds of a forming machine of the Owens type, that is, a machine in which the final molds are swung down about a horizontal axis to a position such that the longitudinal axis of the article to be removed from the mold is at an angle to the vertical.

A further object of the present invention is to provide apparatus of the character above set forth, in which all of the various features and advantages of the device of my prior patent above mentioned are included, and which is further adapted for use with Owens-type machines, whether operated continuously or intermittently.

A further object of the present invention is to provide in a device of the character described a means for steadyng the lower portion of an article being removed from a mold at a position in which its longitudinal axis is inclined to the vertical and preventing the distortion of that article in transferring it from this inclined position to its normal vertical position.

Further objects of my present invention include certain particular mechanisms and adjustments, all of which will be apparent from a reading of the following specification and subjoined claims when taken in connection with the accompanying drawings, in which

Figure 1 is a plan view of a takeout mechanism embodying my invention with portions of the shaping machine and the conveyor for receiving the ware from the takeout; and

Fig. 2 is an elevation of the machine of Fig. 1, certain parts being shown broken away, omitted, and/or in vertical section.

In my prior patent above referred to, there is shown and described a takeout device for removing ware from the final molds of a forming machine in which the final molds may rotate continuously about a vertical axis, but in which the

final molds are permanently upright upon the mold carrier. In the well-known commercial Owens machines, the final molds are mounted upon arms pivoted to the mold carrier for movement about horizontal axes tangent to a circle, 60 the center of which is the axis of rotation of the mold carrier. Prior to the opening of the molds, they are swung downwardly from their position in which the articles are finally blown to a position in which the longer and normally vertical 65 axes of the articles are at an angle (sometimes inclined and sometimes substantially horizontal) to the vertical. The usual practice in operating machines of this general type is merely to open the molds allowing the articles to fall out of 70 them and usually down a chute where they may be manually picked up and set upright by takeout boys. In certain instances, this has caused damage to the ware due to contact of articles with each other, and also due to deformation 75 due to the rough handling of the somewhat semi-plastic ware.

The present invention provides a means for rendering the operation of removal of the articles from molds of machines of this type entirely automatic, and thus dispenses with the services of the boys used in setting up the articles, as well as prevents the distortion or other injury to the articles incident to the manner in which they have been handled in the past.

To a major extent, the present device is constructed along the lines of the device of my prior patent, but includes in addition and in combination with the structures therein disclosed, mechanism for adapting that structure to the removal 90 of articles such as bottles from molds positioned as are the final molds of the well known commercial Owens machine.

Referring to the drawings, there is illustrated a fragmentary portion of an Owens type of machine including a large gear 1 rigidly mounted upon the final mold carrier of the machine and in the usual case adapted for continuous rotation. Mounted in the usual way as above set forth upon the mold carrier is an arm, the end of which is shown at 2 (Fig. 2), this arm being pivoted about a horizontal axis (not shown) so that the mold 3 carried thereby may be lowered from its final blowing position to the position illustrated in the accompanying drawings, which is the normal position at which these molds are opened. The mold 3 is provided with the usual bottom plate 4 and is of the split variety, including halves pivoted for opening and closing movement about a pintle 5 carried by the arm 2.

The takeout mechanism is mounted on a shaft or standard 6 slidably mounted in a bearing member 7 which may be mounted upon any suitable fixed base (not shown). The shaft 6 is prevented from turning by a spline or key 8 in the bearing member 7, thus permitting vertical movement of the shaft 6 while preventing its rotation. Rotatably mounted on the shaft 6 is a gear 9 for actuating the takeout device. The teeth of the gear 9 mesh with those of the driving gear 1 which, as above set forth, is suitably connected to the mold support of the forming machine. The takeout may, if desired, be driven by an independent mechanism. In any case, the mechanisms will be so timed as to cause successive molds and takeouts to arrive at the takeout zone or station at the same time.

The takeout implements, here shown as tongs 10, are provided with properly shaped ware engaging portions 11 designed to engage the particular type of ware being made by the shaping machine. The tongs 10 are removably secured to tong arms 12 by providing a pair of apertures in each of the tongs through which extend studs 13 projecting upwardly from the tong arms, suitable thumb screws 13 being provided for holding the tongs in engagement with the tong arms. The tong arms 12 are pivoted at 14 to tong carrying members 15 and are closed by tension springs 16 extending between the tong arms 12. The tong carrying members 15 are pivoted to slide members 17 on horizontally disposed pintles 18. The slides 17 are each mounted between guides 19 on the outer end of the takeout arms or supports 20, the left hand arm (as seen on the drawings) being supported by a bearing 21 journaled on the shaft 6 and the right hand arm (Fig. 2) having a bearing 22 journaled on the bearing 21. The takeout arms 20 are independently revoluble relative to each other and are moved by levers 23 connected to the outer ends of the arms 20 by links 24. The levers 23 are pivotally supported upon a bracket 25 rotatably mounted upon the shaft 6, the bracket 25 being adjustably secured to the gear 9 by suitable clamp screws 26 extending through circumferentially elongated slots in the flange portion 27 of the bracket.

Interposed between the takeout arms 20 and the levers 23 is a stationary cam member 28, secured to the shaft 6 in any desired manner. The levers 23 are provided with angular extensions 29 having upstanding rollers 30 projecting into the cam groove 31 of the cam member 28. While the speed of the gear 9 will be constant (for a continuously rotating forming machine), the speed of each takeout arm 20 will vary during its revolution at the points and to the extent desired. Such variation is obtained by the proper shaping of the cam groove 31.

Coincident movement of the tongs with the ware and in the mold path may be provided for any desired time, preferably sufficiently long for the tongs to engage the neck or projecting portion of the article in the mold, for the mold then to open and for the tongs then at least to commence the movement of the ware away from the mold. This is accomplished according to the present invention in two ways, first by the angular movement of the tongs carrying member 15 with respect to the tong arm 20 and slide 17 about the axis of the pintle 18. For this purpose, means are provided for moving the tongs carrying member 15 in both directions with respect to the slide 17 by which they are carried.

In the embodiment of the invention shown, the

pintle 18 is rigidly connected to the tongs carrying member 15 and is journaled in projections of the slide 17. One end of the pintle 18 is turned over as illustrated at 32 (Fig. 2), and to this end is connected one end of a tension spring 33, the other end of which is secured to a pin 34 threaded into the slide 17 and passing through a slot 35 in the guideway 19 in which the slide 17 moves. The spring 33 constantly tends to urge the tongs carrying member 15 and the tongs carried thereby to the position shown at the right in Fig. 2, in which the article is carried by the tongs 10 with its longitudinal axis substantially vertical. For moving the tongs angularly about the axis of the pintle 18, the tongs carrying member 15 is provided with a downward extension 36 at the lower end of which is a cam roller 37. A suitably shaped cam member 38 is secured to the cam 28 as illustrated in Fig. 2. Thus the tongs 10 will be moved from their horizontal position, as seen at the right in Fig. 2, to their inclined position, seen at the left in that figure, when approaching the takeout zone, and maintained in that position during their passage through the zone. The cam roller 37 is maintained against the cam 38 and the tongs 10 returned to their horizontal position by the action of the spring 33. By properly shaping and locating the cam 38, the tongs 10 are caused to assume the proper angular position with respect to the arm 20 to engage the neck portion of a bottle or other article in the mold, as illustrated at the left in Fig. 2.

Radial movement of the slide 17 to maintain the tongs in coincidence with the mold path the required length of time is controlled by a stationary cam 39 in conjunction with the revolving movement produced by the cam track 31, the resultant of these movements being the coincident movement of the tongs with the ware.

The cam 39 engages rollers 40 mounted on suitable studs extending upwardly from the slides 17. The slides 17 are provided with threaded studs 41 extending radially inward of the arms 20 and passing through webs 42 connecting portions of the arms 20. Intermediate the webs 42 and the slides 17 and surrounding the studs 41 are compression springs 43. Determination of the limit of the outward movement of the slides 17 is effected by a pair of lock nuts 44 threaded on the studs 41 and adapted to engage the inner sides 45 of the webs 42.

As the tongs approach coincident movement with the mold, they are first moved upwardly to their angular position illustrated at the left in Fig. 2 by the engagement of the rollers 37 with the cam 38. It is then necessary to open the tongs and thereafter to maintain them in open position until they are ready to be closed in engagement with the ware after being lowered on opposite sides thereof. The opening of the tongs is effected by the operation of the intermeshing gear segments 45 suitably secured to or formed as a part of the tong arms 12, a cam 46 being provided to operate the crank arm 47 which is provided with a roller 48 at its end for engagement therewith. Movement imparted to the roller 48 is transmitted through the arm 47 to one of the tong arms 12 and therefrom through the intermeshing gear segments 45 of the other tong arm. The cam 46 opens the tongs prior to their arrival over the ware and holds them open until the arms of the tongs are lowered on opposite sides of the neck or other portion of the ware to be gripped. The spring 16 then closes the tongs about the ware as or before the mold is opened.

After the opening of the mold, the takeout continues to advance and is elevated by mechanism presently to be described, and the ware is lifted from the bottom plate 4 before the tongs are moved out of coincidence with the mold path.

The slide operating cam 39 and the tong opening cam 46 are each removably secured to the bracket 49 by screws 50 and 51 respectively, so that cams of different sizes and shapes may be substituted therefor to effect the desired movements. It will be noted that screws 51, which secure the cam 46 to the bracket 49, pass through slots 52 disposed substantially tangentially of the takeout structure, and screws 50 which secure the cam 39 to the bracket 49 pass through slots 53 disposed substantially radially of the bracket 49. Also the bracket 49 may be angularly adjusted about the shaft 6 by loosening the clamp screw 54 securing this bracket to the shaft 6 and rotatably adjusting the bracket 49 about the shaft 6. In this way the cams 39 and 46 may be adjusted as may be desired to provide for the proper operation of the device, particularly for the proper timing of the closing of the tongs in the case of cam 46, and for the proper following or coincident movement of the tongs with the ware in the mold in the case of cam 39.

The ware delivering or discharging station may be located directly opposite the takeout station or at any desired point in the takeout path. The receiving apparatus may be a belt 55 or a revolvable or stationary table or any other suitable type of receiver or conveyor which may be actuated either intermittently or continuously and in timed relation to the takeout, and may be arranged to move the ware away from the takeout path at any desired angle relative thereto.

When delivering the ware to a stationary receiver or to a conveyor, as that shown in 55 moving away substantially at right angles, the takeout is brought substantially to rest over the belt 55 before releasing the ware. The cam groove 31, when shaped as indicated between the points 51 and 57, will permit the right hand lever 23 to be moved by the continuously rotating bracket 25 without substantial movement of the corresponding arm 20, thus permitting the arm to be retarded or to remain at rest at the delivery station the desired length of time, long enough to effect the delivery of the ware to the conveyor 55. From the time the roller 30 reaches the point 57 of the cam groove 31, a rapid advance of the takeout arm 20 is produced so as to bring the tongs from the takeout station at the time 55 and at the speed desired to effect removal of the ware from the next succeeding mold, all of which is effected by the proper shaping of the cam path 31 and the radial movement of the slide 17 in conjunction with the angular movement of the tongs 60 10 about the axis of the pintle 18.

The opening of the tongs to release the ware at the delivery station is effected by the movement of an arm 58 into engagement with the roller 48 which, as before stated, actuates the tongs. The arm 58 is mounted on the upper end of a shaft 59, rotatable in a bearing member 60, and is held in inoperative position by a spring 61 tending to move the shaft and the arm 58 clockwise. A pin 62 on the shaft 59 engages an abutment on the bearing 60 and serves to limit the clockwise movement of the arm 58.

Movement of the arm 58 counterclockwise to the operating position shown in Fig. 1 is effected by a second arm 63 secured to the shaft 59 and having a roller 64 in the path of an adjustable

cam 65 on the gear 9, a separate cam being provided for each of the takeout arms. The cams 65 are adjustable to the desired positions and are held by the clamp screws 66 extending through the slots 67 of the cams. The tongs opening mechanism just described may be so positioned as to effect their opening at any suitable point in the take-out path at which it may be desired to discharge the ware.

The takeouts are each lowered twice in a single revolution, first at the takeout station to be closed about the ware, and later at the delivery station to deposit the ware upon the conveyor. The raising and lowering is effected by providing on the underside of the gear 9 a cam ring or circular track 68 resting upon the rollers 69 carried by the oppositely disposed bracket 70. The track is provided with like cam surfaces or depressions in which the rollers are located in the position of the device shown in Fig. 2, these depressions being diametrically opposed to each other permitting the mechanism to be lowered when the takeouts are in the position shown in the drawings and elevating it in other positions, whereby the ware is lifted by the tongs at the receiving or takeout station and the tongs are raised at the delivery station above the top of the ware just delivered. However, where the conveyor 55 moves continuously, the ware may move out from between the tongs before they are raised. During the raising and lowering of the takeout mechanism, the teeth of the gear 9 will slide upon the teeth of the gear 1 and the end of the shaft 6 will slide in the bearing member 7.

Means are also provided for steadyng the lower portion of an article being removed from the mold in the inclined position shown at the left in Fig. 2. Such means include a steadyng member, generally indicated at 71 and provided with a resilient or spring clip contactor 72 which will engage the lower portion of an article gripped by the tongs 10. The member 71 is pivoted on a horizontal axis at 73 to a bracket 74 which is suitably secured to the tongs carrying member 15. The end of the member 71 opposite that to which the contactor 72 is attached is extended beyond the pivot 73 and connected to the suitable fixed part of the tongs carrying member 15 by a tension spring 75 which constantly tends to urge the bottom steadier into its operative position with respect to the tongs, at which position it will steady the lower portion of an article gripped thereby. Means are also provided for adjustably limiting the movement of the member 71 under the action of the spring 75, that is, the movement of this member toward its operative position. Such means include a shoulder 76 formed on the member 71 and adapted to contact with the end of an adjustable stop screw 77 threaded through the bracket 74 and secured in adjusted position by a suitable lock nut 78.

The operation of this bottom steadier is as follows: As the tongs approach the takeout position and approach the path of movement of the ware in the mold, which is to be removed, the contactor portion 72 of the steadier will engage the outside of the then closed mold 3, so that as the tongs continue to approach and actually reach the portion of their path in coincidence with the mold, the member 71 will be moved about its pivot 73 by contact with the outside of the mold, and by extending the spring 75. When the mold 3 is opened, the spring 75 will be effective to move the arm 71 to the position shown at the left in Fig. 2, which is the operative position for

- the steadier. At this position the resilient contactor member 72 will engage and steady the lower portion of the article which is being freed by the opening mold. This engagement will be maintained throughout the transfer of the article to the delivery station, as seen at the right in Fig. 2, thus preventing distortion of the article due to the action of gravity thereon and the support thereof by its neck in an inclined position.
- 10 While in the above description and in certain of the appended claims I have referred to the articles being handled as "bottles", I do not wish this term to be construed in any limiting sense, but rather intend that it be considered as referring to any articles of glassware which may be made in a machine of the Owens type as above defined and/or which may be handled by the device forming the subject matter of this invention.
- 15 While I have shown and described but one embodiment of my invention, it will be understood that various changes may be made in the construction and form of the entire apparatus or various parts thereof, and that equivalent constructions or mechanisms may be employed without departing from the spirit of the invention as embodied in the appended claims, which are to be construed as broadly as the state of the prior art permits.
- 20 I claim:
- 30 1. Apparatus for removing articles of glassware from partible molds in which the articles are formed, comprising a support, tongs on said support for gripping the upper portion of a glass article projecting above the mold prior to the opening thereof, means for opening and closing said tongs, means for moving said support to move said tongs into such position relative to said mold that the tongs may grip the upper portion of a glass article projecting from the closed mold and then for moving said support subsequent to the opening of said mold to move the article gripped by said tongs to a delivery position, an arm pivoted to said support on a horizontal axis having a portion adapted to engage and steady the lower portion of a glass article gripped by said tongs, means for resiliently urging said arm to its operative position with respect to said tongs while permitting movement of said arm relative to said tongs upon its contact with the initially closed mold, and means for determining the operative position to which said arm is moved with respect to said tongs upon the opening of the mold.
- 35 2. Takeout apparatus for removing bottles from the final molds of a bottle forming machine of the type in which the final molds from which the bottles are to be removed are mounted for rotation about a vertical axis and are adapted to be opened for the discharge of the bottles in a position in which the longer axes of the bottles are at an angle with the vertical, comprising an arm mounted for rotation about a vertical axis spaced from the axis about which the final molds of the forming machine rotate, means for rotating the arm in synchronized time relation with the movement of said molds at least during their passage through a takeout zone, a tongs carrying member mounted for pivotal movement with respect to said arm about a horizontal axis substantially perpendicular to the longitudinal axis of said arm, means for moving said tongs carrying member about its pivot with respect to said arm, tongs on said tongs carrying member for gripping the neck portion of the

80 bottle while it is still enclosed by the mold in which it was formed, means to open and close said tongs, and steadyng means also carried by said tongs carrying member for engaging and steadyng the lower portion of an article gripped by said tongs during the movement of the article from a position it occupied in the mold in which its axis is at an angle with the vertical to a delivery position in which its axis is substantially vertical.

85 3. Takeout apparatus for a bottle forming machine of the type in which the final molds from which the bottles are to be removed are continuously rotated about a vertical axis and are adapted to be opened for the discharge of bottles in a predetermined zone and in a position in which the longer axes of the bottles are at an angle with the vertical, comprising an arm mounted for rotation about a vertical axis spaced from the axis about which the final molds of the forming machine rotate, means for rotating said arm, a member mounted for substantially radial sliding movement with respect to said arm, a tongs carrying member pivotally mounted upon the sliding member for movement about a horizontal axis arranged substantially tangent to a circle the center of which is the axis of rotation of said arm, tongs mounted upon said tongs carrying member, means to open and close said tongs, means to move said tongs through a path 90 and at a speed such that the tongs follow the path of movement of the portion of an article in the final molds to be gripped by the tongs both before and after the opening of the molds, means for retarding the angular speed of rotation of said arm adjacent to a delivery zone for the deposit of an article by the tongs in this zone and thereafter for accelerating the angular speed of movement of the arm, means for moving the tongs carrying member and the tongs carried thereby vertically for assisting in the removal of articles from the molds in which they were formed and thereafter for depositing the articles in the delivery zone, and article steadyng means also carried by said tongs carrying member for 95 engaging and steadyng the lower portion of an article gripped by said tongs in a position in which the longer axis of the article is at an angle to the vertical and during its movement to a position in which this longer axis is substantially 100 vertical.

105 4. Takeout apparatus for a bottle forming machine of the type in which the final molds from which the bottles are to be removed are mounted for rotation about a vertical axis and are adapted to be opened for the discharge of the bottles in a position in which the longer axes of the bottles are at an angle with the vertical, comprising takeout tongs mounted for movement in an orbital path between a receiving zone adjacent to the path of the mold from which a bottle is to be removed and a delivery zone and also mounted for movement between a position in which the tongs may engage a bottle having its longer axis at an angle with the vertical while 110 in the mold at the receiving zone and a position in which the longer axis of the bottle is substantially vertical at the delivery zone, means for opening and closing the tongs to engage and release a bottle being removed from the mold 115 and transferred to the delivery zone, means for moving the tongs between the receiving and delivery zones, means for moving the tongs angularly with respect to the horizontal to present them in a position to engage a bottle in the mold 120

at the receiving zone and in a position in which the longer axis of the bottle is substantially vertical at the delivery zone, a steadyng member mounted for movement with the tongs and also for movement with respect thereto about a substantially horizontal axis, means for resiliently urging the steadyng member toward a position in which it is adapted to engage and steady the lower portion of an article gripped by the tongs, and means for preventing further movement of the steadyng member about its pivot with respect to the tongs after it has reached its operative position with respect thereto, whereby the steadyng member will engage the outside of the mold prior to the opening thereof and will be moved to its operative position to steady an article gripped by the tongs upon the opening of the mold.

5. Takeout apparatus for a bottle forming machine of the type in which the final molds from which the bottles are to be removed are mounted for rotation about a vertical axis and are adapted to be opened for the discharge of the bottles in a position in which the longer axes of the bottles are at an angle with the vertical, comprising an arm mounted for rotation about a vertical axis spaced from the axis about which the final molds of the forming machine rotate, means for rotating said arm in synchronized time relation with the movement of said molds at least during their passage through a takeout zone, a tongs carrying member mounted for pivotal movement with respect to said arm about a horizontal axis substantially perpendicular to the longitudinal axis of said arm, means for moving said tongs carrying member about its pivot with respect to said arm, tongs on said tongs carrying member, means to open and close said tongs, a ware steadyng member mounted on said tongs carrying member for movement about a horizontal axis below said tongs for engaging and steadyng the lower portion of an article gripped by said tongs, means for resiliently urging said ware steadyng member toward an operative position with respect to said tongs in which it engages an article gripped therein, and means for adjustably determining the operative position of said ware steadyng member, whereby said ware steadyng member will engage the outside of the mold from which an article is to be removed prior to the opening of that mold and will be moved automatically to its operative position to steady an article engaged by the tongs upon the opening of the mold.

6. Takeout apparatus for a bottle forming machine of the type in which the final molds from which the bottles are to be removed are continuously rotated about a vertical axis and are adapted to be opened for the discharge of bottles in a predetermined zone and in a position in which the longer axes of the bottles are at an angle with the vertical, comprising an arm mounted for rotation about a vertical axis spaced laterally from the axis of rotation of the molds from which the articles are to be removed, tongs carried by said arm, means providing for the movement of said tongs with respect to said arm in a direction substantially radial to the axis of said arm, means providing for the movement of said tongs with respect to said arm about a horizontal axis substantially perpendicular to the longitudinal axis of said arm, means for moving the tongs through a path a part of which follows the path of movement of the molds through the zone in which the ware is to be removed therefrom, means for opening and closing the tongs in predetermined adjustable time relation to the time of opening of the molds for the release of the articles formed therein, and means moving with the tongs for engaging and steadyng the lower portion of an article gripped thereby upon the opening of the mold in which it was formed.

7. Takeout apparatus for a bottle forming machine of the type in which the final molds from which the bottles are to be removed are continuously rotated about a vertical axis and are adapted to be opened for the discharge of bottles in a predetermined zone and in a position in which the longer axes of the bottles are at an angle with the vertical, comprising an arm mounted for rotation about a vertical axis spaced from the axis about which the final molds of the forming machine rotate, means for rotating said arm, a slide member mounted on said arm and resiliently urged to its outermost radial position with respect thereto, a tongs carrying member mounted on said slide member for movement about a horizontal axis tangent to a circle the center of which is the axis of rotation of said arm, tongs on said tongs carrying member, cam means for controlling the radial position of said slide member with respect to said arm in response to the rotation of the latter, other cam means for controlling the angular position of said tongs carrying member with respect to said slide member subject to the rotation of said arm, means for opening and closing said tongs, the several cam means and the arm rotat- ing means being so constructed and arranged that the gripping portion of said tongs follows the path of movement of the portion of an article in said mold to be gripped by the tongs through a predetermined zone in the movement of the mold, means for raising and lowering the tongs for assisting in the removal of an article from said mold and thereafter for assisting in the placing of the article at a delivery station, a bottom steadyng member pivotally connected to said tongs carrying member for movement about a horizontal axis, means for resiliently urging the bottom steadyng member to an operative position with respect to said tongs at which it engages and steadyng the lower portion of an article gripped by said tongs, and means for adjustably determining the operative position of the bottom steadyng member.
